E. A. Trussell

Inventor:—
Emory A. Trussell.
By *Wm. H. P. T. Atty's.*

UNITED STATES PATENT OFFICE.

EMORY A. TRUSSELL, OF ST. LOUIS, MISSOURI, ASSIGNOR TO THE SIEBER & TRUSSELL MANUFACTURING COMPANY, OF ST. LOUIS, MISSOURI, A CORPORATION.

TEMPORARY BINDER.

SPECIFICATION forming part of Letters Patent No. 700,388, dated May 20, 1902.

Application filed July 21, 1900. Serial No. 24,373. (No model.)

To all whom it may concern:

Be it known that I, EMORY A. TRUSSELL, a citizen of the United States, residing at the city of St. Louis, in the State of Missouri, have 5 invented certain new and useful Improvements in Temporary Binders, of which the following is a full, clear, and exact description, reference being had to the accompanying drawings, forming part of this specification.

10 My invention relates to that class of devices used for holding loose sheets or detached leaves of paper, the object of the invention being the production of a binder of the character named wherein two pairs of 15 arch-prongs are utilized upon which the loose sheets or leaves are placed and from which they are readily released upon moving the covers of the binder back to back instead of the operation of relieving the arch-prongs 20 from resistance, as in other devices of this nature, when it is desired to remove or insert sheets from or into the binder.

Figure I is a perspective view showing my improved binder in open position. Fig. II is 25 an enlarged detail view of the arch-prong-carrying frames, the prongs, and means by which they are connected. Fig. III is a cross-sectional view taken on line III III, Fig. II. Fig. IV is an enlarged cross-sectional view 30 taken through the binder-covers, back, and prong-carrying frames and showing the arch-prongs in elevation. Fig. V is a detail end view of the binder, showing it in the position assumed for the insertion or removal of loose 35 sheets. Fig. VI is a detail view, partly in section, of a fragment of the binder-back and one of the arch-prongs. Fig. VII is a cross-sectional view of the rear portion of the binder with the parts shown in the positions assumed when the binder is closed.

40 1 designates the covers of the binder, that are joined to the back 2 by interposed sections 3, connected to the parts through flexible hinges 4 and 5. The construction of the 45 covers, the back, and the connections between these parts is not, however, essential in so far as my invention is concerned, and they may be altered at will.

46 6^a designate strips, preferably of metal, 50 and 7 7^a are plates secured to said strips by

rivets 8 8^a. The covers 1 are designed to be secured between the strips 6 6^a and plates 7 7^a and are held in position between such parts by rivets inserted through perforations (see Fig. II) in such strips and plates. Seated 55 between the strips and plates are hinge-arms 9 9^a, that are held by the rivets 8 8^a, the covers 1 being notched at the location of said hinge-arms to permit of the insertion of the covers between the plates and strips by which 60 they are held. The hinge-arms are joined by a hinge-rod 10, that passes through said arms, that is suitably held from escape therefrom. From the foregoing it will be seen that a hinge connection is provided between the 65 inner edges of the covers 1, upon which said covers move independently of the back 2 of the binder.

11 11^a designate arch-prongs, the base end of each of which is rigidly fixed to either the 70 hinge-arm 9 or the hinge-arm 9^a, the said arch-prongs being curved inwardly toward each other and having their points flattened on the under sides, as clearly shown, and also being of sufficient length that they will overlap each other when the binder is opened out 75 into flat position, as seen in Figs. I, II, III, and IV.

A designates loose sheets or leaves of the form designed for use in the binder, each 80 sheet or leaf being provided with two pairs of perforations B C, (see Fig. I,) through which the opposing prongs 9 9^a are adapted to pass, the inner prongs entering the inner perforations B and the outer prongs entering the outer 85 perforations C as the sheets or leaves are placed thereon or transferred from one side to the other of the binder.

In the practical use of this binder the loose 90 sheets or leaves are inserted therein when the arch-prongs 11 11^a are separated, as shown in Fig. V, by throwing the covers 1 rearwardly so that their outer backs approach each other, thereby permitting the ready application of the leaves A to either of the arch-prongs 11 95 11^a by slipping them thereon without the necessity of releasing any parts to permit the separation of the prongs, as is commonly the case in devices of the nature to which my invention belongs. When the sheets or leaves 100

have been placed on the prongs and the covers are moved into flat position with the binder open, as shown in Fig. I, the prongs assume the position seen in said last-named figure, in which their ends overlap, thereby preventing the escape of the sheets or leaves from the arches produced by the opposing prongs. The prongs being arranged in alignment with each other, so as to provide complete arches, the sheets or leaves may be readily moved thereon from side to side of the binder, the prongs at the receiving side entering their respective perforations in the sheets or leaves, and the transference of the sheets or leaves being most easily permitted by reason of the prongs being flattened on their under sides so that the completed arches are of the same diameter from base to base of the opposing prongs. On the closing of the binder the arch-prongs all pass through their respective perforations in the loose sheets or leaves and into the space within the back of the binder, as seen in Fig. VII, where they securely hold the sheets or leaves from

escape. It will be observed that the hinge-arms 9^a extend to points approximately central of the distance between the bases and points of the arch-prongs and are connected at such locations so that the prongs are caused to swing upon a true arc, whereby their movement is in unison and in the necessary portion of a circle to permit the free action and travel of the prongs in all other positions into which the binder is moved.

I claim as my invention—

In a temporary binder, the combination of a pair of covers, hinge-arms pivotally united and seated in said covers, prongs carried by said arms, a plate secured to each of said arms, and strips providing connections between corresponding hinge-arms on the same side of the hinge; said covers being secured between said plates and strips, substantially as described.

EMORY A. TRUSSELL.

In presence of—

NELLIE V. ALEXANDER,
M. P. SMITH.
